RECORD MECHANISM

Howard D. Colman, Rockford, Ill., assignor to
Barber-Colman Company, Rockford, Ill., a corporation of Illinois

Application August 2, 1941, Serial No. 405,143

11 Claims. (Cl. 178—17.5)

The invention pertains to a record mechanism for the storage of intelligence for subsequent utilization in the control of automatic machines, mechanism or apparatus, and has particular reference to a record mechanism of the type having a storage medium in the form of an elongated flexible band such as a tape or chain.

The primary object of the invention is to provide a record mechanism of improved construction having a storage medium in the form of a flexible band with means for advancing the band relative to two spaced points independently, and with the band effectually supported and guided so as to permit of variations in the length of the portion between said points through a relatively wide range without the production of slack.

Another object is to provide in a record mechanism of the type having a storage medium in the form of an endless band, means effectually supporting and guiding the band in the form of a loop shiftable endwise to compensate for a differential rate of advance of the band at opposite sides of the loop.

A further object is to provide a record mechanism having a shiftable support upon which the endless band is mounted to form an elongated loop capable of bodily movement with the support relative to two stationary points disposed on opposite sides of the loop or, alternatively, of movement relative to the support past said points.

This application is a continuation in part of my copending application, Ser. No. 319,047, filed November 13, 1928, for a System of communication.

The objects of the invention above set forth together with other and ancillary advantages are obtained by the construction and arrangement set forth by way of example in the accompanying drawings, and hereinafter described herein.

Figure 1 is a side elevational view of a record mechanism embodying my invention, the portions of the framework and sprocket shafts being shown in section.

Fig. 2 is a fragmentary front elevational view with the recording device and drive means for the outer run of the loop being omitted for sake of clearness.

Fig. 3 is a fragmentary transverse sectional view taken approximately along the line 3—3 of Fig. 2.

Fig. 4 is a fragmentary side elevational view of the chain constituting the record medium, a portion thereof being shown in section.

Fig. 5 is a view generally similar to Fig. 1, but showing a somewhat modified construction.

The improved record mechanism comprises generally a record or storage medium in the form of a flexible band herein shown as a chain 4 mounted for movement with or relative to an elongated supporting structure so as to form a loop 6. The supporting structure is suitably guided for bodily shifting movement in an endwise direction and thus constitutes in effect a car 43 which remains stationary or moves in one direction or the other according to the operation of two drive means respectively disposed on opposite sides of the loop.

The chain constituting in the present embodiment the flexible storage medium is especially adapted for use in the storage of telegraphic signals as fully disclosed in the prior application, Ser. No. 319,047. However, it will be understood that the particular construction of the chain will vary according to the nature of the intelligence to be stored thereon and forms per se no part of the present invention. As shown herein, it is composed of a series of pivotally connected links carrying settable elements such as rows of pins 8 shiftable axially into either of two set positions to form code combinations individually representative of message characters or control signals. Each link comprises two spaced parallel bars 9 connected by end plates 10 which in turn are connected by pintles 12, the ends of which carry studs 13 adapted to be engaged by pairs of sprockets or rollers for guiding and advancing purposes.

The loop 6 has a substantially fixed overall length as determined by the car 43. The latter comprises two pairs of spaced idler rolls or sprockets 44 and 44' rotatable on shafts 45 journaled respectively in pairs of upper and lower blocks 46 and 46' and each slidably in suitable guideways 47 of a stationary framework. The blocks 46 and 46' are connected through the medium of links 48, and in order to maintain the chain taut each of the upper blocks is made in two telescoping sections urged apart by a spring 49.

As shown in the aforesaid application, the loop 6 forms a part of a signal storage mechanism having a main section (not herein shown) of large capacity, the loop being shiftable bodily independently of the remainder of the chain.

To form the loop the chain passes around two pairs of sprockets engaging the chain at closely spaced points. Thus the chain is led from a source of supply (not shown) around a pair of sprockets 50' on a shaft 50 and then successively around the lower and upper idlers 44' and

44 and finally around sprockets 28' on a shaft 28 from whence it passes into the main section of the storage mechanism. The shafts 28 and 50 are stationarily mounted in closely spaced parallel relation and are connected by a gear train shown in dotted lines in Fig. 1 and comprising gears 29 and 30 on the shafts 28 and 50 respectively, and an idler pinion 31. Thus the sprockets 28' and 50' rotate in unison and together constitute a single or inner drive means for advancing the chain at one side of the loop. The opposite side of the loop presents an outer straight run which is advanced by a second or outer drive means comprising a pair of sprockets 53 on a shaft 76 suitably mounted in the frame structure.

The two drive means thus associated with the chain at opposite sides of the loop are arranged to be actuated independently and the loop will remain stationary or shift bodily in one direction or the other according to the manner in which the two drive means are operated. Thus, if the sprockets 53 are driven in a direction to move the outer run 51 of the chain upwardly while the shafts 28 and 50 of the other drive means are stationary, the car 43 and the loop thereon will move upwardly. But, if said shafts rotate in the direction indicated by the arrow in Fig. 1 and the sprockets 53 are stationary, equal lengths of the chain will be fed into and drawn out of the loop and the car will move downwardly. On the other hand, if the two drive means on opposite sides of the loop operate simultaneously to advance the chain at each side at the same rate, the car and the loop formed thereon will remain stationary.

The means for actuating the two drive means at opposite sides of the loop form per se no part of the present invention. As disclosed in the aforesaid application, Ser. No. 319,047, the shafts 28 and 50 are operatively associated with a suitable clutch controlled mechanism (not herein shown) adapted to feed chain into and withdraw it from the loop 6; and the shaft 76 carrying the sprockets 53 is actuated by another clutch controlled mechanism operable to advance the outer run of the chain upwardly as an incident to the recordation of signals upon the chain.

Before entering the loop 6, the chain passes over a suitable blander (not shown) operative to position the pins 8 uniformly for presentation to a signal responsive recording device 154 of any suitable or preferred character, as for example, that shown in said parent application. Said recording device is herein shown as located somewhat below the sprockets 53 and operates to record signals upon the outer run of the chain as it is advanced upwardly by said sprockets. It will be seen that if the sprockets 28' and 50' remain stationary in this operation, the chain will be withdrawn from the lower portion of the loop between the sprockets 50' and 53, and a gradually increasing length thereof will be introduced into the upper portion of the loop above said two pairs of sprockets. Conversely, if the sprockets 28' and 50' are actuated while the sprockets 53 remain stationary, the length of chain in the upper portion of the loop will decrease and that in the lower portion of the loop will increase. In either case, the car 43 moves endwise in one direction or the other and the chain is not only maintained taut at all times but is effectually supported and guided with re-

spect to the signal responsive recording device 154.

In some instances where a large storage capacity is not required and it is merely desired to compensate for different rates of advance at two spaced control points the shiftable loop may constitute the entire storage medium. In such event a loop 6' entirely closed may be employed as shown for example in Fig. 5. With the construction shown in Fig. 1 it is of course contemplated that the signals or other intelligence recorded upon the loop 6 will be utilized at another point in the apparatus in the control of a sensing device such as a signal transmitter, the storage or record medium being in the form of an endless band of substantial length, as disclosed in said parent application. When, however, a single closed loop constitutes the entire storage medium, the stored matter is recorded on the chain or band at one side of the loop as at 154' and is utilized for control purposes at the other side of the loop, as by means of a sensing device 413 responsive to the setting of the pins 8 as in said parent application. Thus the loop 6' provides two opposite runs of substantial length with which the recording and sensing devices are respectively associated. Between these devices a variable length of storage medium may be interposed by a shifting of the car to compensate for a differential rate of advance of the storage medium at opposite sides of the loop, the two drive means, as in the preceding instance, being capable of advancing the chain in the two opposite runs independently or at different rates. As shown, they comprise two pairs of sprockets 54 and 55 respectively mounted on shafts 56, 57. In other respects the construction is similar to that of Figs. 1 to 4. It will of course be understood that before re-presentation to the recording device 154' the pins 8 will be reset by means of a blander 60 of any suitable or preferred character.

I claim as my invention:

1. A record mechanism having, in combination, 45 a record medium comprising a band, sprockets engaging said band at spaced points, means for driving said sprockets to maintain a constant length of band between them, a resiliently extensible and contractible member supporting the band between said sprockets in the form of an elongated loop, a recording device operatively associated with a portion of said loop, and means for advancing said portion in one direction.

2. A record mechanism having, in combination, 55 a storage medium comprising a band, a pair of spaced sprockets engaging said band and rotatable on fixed parallel axes, a member supporting the portion of said band between said sprockets for bodily movement and forming an elongated loop of invariable length with a substantially straight run opposite said sprockets, a recording device operatively associated with the band, means for advancing said run whereby to move said member in one direction, and other 60 means operable to drive said sprockets in a direction to move said member in the opposite direction.

3. A record mechanism comprising, in combination, 70 a flexible record medium, a pair of sprockets engaging said record medium at spaced points to form a bodily movable loop between said points, a recording device, and means operable to advance the record medium relative to said device and in a direction to cause bodily movement of said loop in one direction, one of

said sprockets being operative to cause bodily movement of said loop in the opposite direction.

4. A record mechanism comprising, in combination, a flexible record medium, a car having idler sprockets at opposite ends thereof, said record medium being reeved over said idler sprockets to form an elongated loop, means supporting said car for endwise shifting movement, a recording device disposed at one side of said car in operative relation to the record medium, means operable to advance the record medium relative to said device and in a direction to cause bodily movement of said loop in one direction, and means engaging with said record medium on the opposite side of the loop for advancing the same in a direction to cause bodily movement of the loop in the opposite direction.

5. A record mechanism comprising, in combination, a car guided for endwise movement and comprising a pair of journal blocks, means holding said blocks in spaced relation, and idler sprockets carried by said blocks, a chain reeved over said sprockets and movable bodily with the car, said chain having settable elements thereon for record purposes, setting means stationarily mounted at one side of the car in operative relation to said elements, and drive sprockets engaging said chain at opposite sides of the car and adapted for operation independently to move the chain relative to said device, either with or relative to the car.

6. A record mechanism comprising, in combination, an elongated member guided for endwise movement and constituting a car, guide elements at opposite ends of the car, a record medium in the form of a band passing over said elements to form a loop closely encompassing the car, and differentially operable drive means stationarily mounted on opposite sides of the car and each arranged in operative association with said band to control the advance of the band on opposite sides of the car, said car moving bodily when the band is advanced differentially at opposite sides of the car whereby to vary the length of the record medium interposed between said differentially operable drive means.

7. A record mechanism comprising, in combination, a car guided for endwise movements, idler sprockets at opposite ends of the car, a chain having settable elements thereon, reeved over said idler sprockets and forming an elongated run on at least one side of the car, a device disposed adjacent said elongated run and in operative association with the settable elements of the chain, and means for driving the chain comprising oppositely disposed sprockets engaging with the chain at either side of the car, said elongated run of the chain being shiftable with the

car and relative to said device by the operation of one of said driving sprockets at a rate different from that of the other sprocket.

5 8. A record mechanism comprising, in combination, a flexible band forming a record medium and arranged in the form of a loop of fixed dimensions and having opposite side portions at least one of which presents an elongated run, a recording device, means for supporting said loop for bodily shifting movements with said run in operative association with the recording device, and means engaging the record medium at either side of the loop and operable to advance opposite side portions thereof differentially.

10 9. A record mechanism comprising, in combination, a flexible band constituting a record medium, means supporting said band to form an elongated closed loop of fixed length, said band being movable relative to said supporting means and said loop together with its supporting means being mounted for bodily shifting movement and having opposite side portions each presenting an elongated run, a recording device associated with one of said runs, a sensing device operatively associated with the other one of said runs, and drive means operative to advance opposite side portions of the loop differentially to carry said record medium past said recording and sensing devices.

15 10. A record mechanism comprising, in combination with recording and sensing devices disposed in spaced relation, a record medium in the form of an endless band, a shiftable support, said band being mounted on said support to form a closed loop having elongated parallel side portions respectively associated with said recording and sensing devices, and drive means stationarily mounted on opposite sides of the loop and each operative to control the advance of said opposite side portions of the loop, said support moving bodily when the opposite side portions of the loop are advanced differentially and said support remaining stationary when the said side portions of the loop are advanced relative to the support at the same rate.

20 45 11. A record mechanism comprising, in combination, an endless band constituting a record medium, means for supporting said band including a pair of idler rolls connected in substantially fixed spaced relation and over which the band is reeved to form two opposing loop portions with opposite runs of substantial length, stationarily mounted recording and sensing devices respectively associated with said two runs, and differentially operable means for advancing said two runs, said idler rolls shifting to compensate for the differential advance of opposite runs.

HOWARD D. COLMAN.
